UNITED STATES PATENT OFFICE.

HENRY S. SCHOPP, OF SPOKANE, WASHINGTON.

METHOD AND MEANS FOR MOLDING VAULT LIDS.

Application filed February 15, 1928. Serial No. 254,521.

The object of this invention is to provide a novel method and means for molding a vault lid on a vault body.

Burial vaults of concrete are very heavy and it is necessary that the lid should not only be the same size, but that it should accurately fit the upper edges of the walls of the vault body.

Now it is a special feature of my invention to first complete the vault body and provide the upper edges of the walls thereof with the proper or desired contour, and then employ the completed vault body as a part of the means or mechanism for molding the lid therefor.

In accordance with my invention, form apparatus is supported on and attached to the completed vault onto which and into which apparatus the concrete or other material of which the lid is to be formed is poured, so that after the lid has set, it will be accurately the size necessary for the vault body.

My improved form apparatus is designed and constructed to coact with the vault walls and the lid being formed thereon, in a manner to provide sealed spaces, which spaces are preferably disposed in what I will term inwardly and outwardly arranged positions with respect to an intermediate strip of contact between the lid and the wall edges.

My invention has other objects and features which will be more fully described in connection with the accompanying drawings and which will be more particularly pointed out in and by the appended claims.

In the drawings:

Fig. 1, is a vertical cross sectional view showing a completed vault body with my improved form mechanism attached thereto and illustrating how the lid is formed thereon.

Fig. 2, is a similar view of the lid shown detached from the vault body.

Fig. 3, is a view of the vault body with a portion of the form mechanism removed therefrom.

Fig. 4, is a top plan view of a supporting form detached from a position of use and showing the same on a reduced scale from that employed in Fig. 1.

Fig. 5, is a bottom plan view thereof.

Fig. 6, is a top plan view of the vault body with the formed lid thereon and show-

ing the manner in which the outer form mechanism is applied.

Like characters of reference designate similar parts throughout the different figures of the drawings.

Reference will first be made to the vault body wherein it will be seen that the same consists of a bottom wall 1, side walls 2 and end walls 3, all of said walls being preferably alike in contour and cross section. 65 This vault body is made of concrete or like plastic material capable of being molded and any desired form mechanism may be used, as far as my present invention is concerned. It may be pointed out that the upper 70 portions of walls 2 are formed of a greater thickness than the lower portions to afford the necessary width of contact with the lid and provide for sealing areas, hence, all the walls are made thicker at 4, and on the outside of the walls, I provide the same with a flat vertically disposed abutment portion 5, the purpose of which will later appear.

The upper edges of the walls are also formed in a novel manner and for a purpose 80 of not only providing novel inner and outer sealing spaces but also disposing said spaces so that they will shed water outwardly and downwardly.

Thus, as clearly shown at the left of Fig. 85 3, the upper edge is provided with a preferably horizontal inner surface 6, which is also a form supporting surface, as will later appear. An intermediate surface 7, which is a lid contact surface, slopes downwardly 90 and outwardly from surface 6. A short outer surface 8, slopes downwardly and outwardly from the intermediate surface 7. I have thus set forth the essential novel features of the upper edge portions of 95 the vault walls and I will next describe the manner and means whereby this configuration is transferred to complementary portions of the lid, in accurate registry therewith, so that the lid is bound to fit 100 the vault.

One of the features of my mold mechanism is in the form of a supporting mold structure which consists in part, of a thin and preferably metal shell 9 which may be 105 flat, as shown, at its central portions but which slopes toward its edges, as indicated at 10, thus providing an arched formation transversely and longitudinally of the form. As a means of stiffening the sheet 110

form, I secure thereto a plurality of form beams 11, as by means of nails or screws 12, to hold the shell 9 to form. It will be seen from Figs. 4 and 5, that these beams extend transversely of the length of said form and it will be clear that they terminate at or just inside the inner faces of the walls 2. This arched form imparts to the lid, a similar form, which strengthens the same irrespective of any re-inforcements that may be employed. I provide the lid supporting form, which as will now be seen, spans the inner walls 2 and 3, with an outwardly extending supporting flange 13. This flange 13, is of a width to seat on the inner section 6, and support the form on walls 2 and 3. Further, this flange 13, is of a thickness sufficient, and preferably only sufficient to form an inner sealing space between the lid 20 and the upper edges, which sealing space extends completely around said upper edges. As a means of stiffening the beams 11, and also as an alining means, I nail or otherwise suitably secure strips 14 and 15 as shown, which strips form abutments that engage the inner faces of walls 2 and 3, to center the supporting form on said walls.

I will next describe the outer or surrounding mold means in which the outer edge portions of the lid are formed.

Said outer form includes mold timbers 16 and 17 which are abutted against the faces 5, and secured by suitable clips 18, at the corners. I prefer to employ a sheet iron or like form 19 and 20, which fits over the timbers 16 and 17, as clearly shown in Fig. 1, and which is provided with a depending portion 21 extending inside the timbers and against which the concrete of the lid extends while being formed. Each form 19 and 20, is in all respects alike in this particular, therefore, and only one need be described in detail. Said form 19 has a space or sealing form extension 22, which extends inwardly slightly above the outer sealing face 8, with which each upper edge is equipped.

Now it will be assumed that the mold mechanism just described is all in place as clearly shown in Fig. 1, with the parts all ready to pour the lid, which I will designate at 23. As a usual expedient, the supporting form will be covered with paper or something of like character to prevent the concrete from adhering thereto, and likewise, the same will be done as regards portions 21 and 22. In the intermediate space 7, between the sealing spaces 6 and 8 a strip of paper 24, will be disposed. Now with these preliminaries accomplished, the concrete will be poured on the form structure and suitably manipulated or troweled to the contour shown. Suitable handles 25 may be disposed in a manner to bury their lower bent ends 26, in the concrete, as shown, and as will be obvious to those skilled in this art.

After the lid 23 has set, the form timbers 16 and 17 will be removed, and then it will be easy to remove the forms 19 and 20. Then, the lid 23 can be lifted by its handles 25, to permit removal of the supporting form, as shown in Figs. 2 and 3. Then, the lid 23, can be lowered onto the vault to so remain until the structure it to be used.

It will now be clear that the vault engaging edge of the lid 23, will have an inner sealing space portion 27, an outer sealing space forming portion 28, and an intermediate fitting or supporting portion 29. Now because of form portions 22 and 13, the lid 23 will only actually engage and come into contact with the upper edges of the vault when portions 29 and 7 contact, assuming that the lid is to be lowered from the Fig. 2, position. Thus, part 27, will be in spaced relation to part 6, and part 28, will be in spaced relation to part 8. It will thus be seen that when the outwardly sloping portions 7 and 29, come into contact, the lid 23 will not only be accurately centered on the vault, but the outwardly lateral sealing space will be below the sealing space formed by 6 and 27, thereby acting to prevent water from entering the vault.

If the casket were disposed in the vault as shown in Fig. 3, a quantity of sealing cement would first be disposed in surface 6, and when the lid 23 was lowered into place, the inner seal would have been formed. By reason of the thickness of the form portion 22, and the advantageous slope of portion 8, there would be an outer sealing space which the operator would trowel full of cement and there would thus be provided an inner and upwardly disposed sealed joint and an outwardly and lowermost disposed sealed joint, with the intermediate portions 7 and 29, between the two, and in close engagement.

It is believed that my invention will be fully understood from the foregoing description, and while I have herein-described one specific feature thereof, I do not wish to be limited thereto except for such limitations as the claims may import.

I claim:

1. In a means for molding a concrete or like vault lid, the combination with a finished concrete vault body with upright walls having top edges, a lid supporting mold form mounted on said vault body and spanning the space between said top edges to receive the major portion of the concrete for forming the lid, and mold members outwardly surrounding said vault body for forming the outer edges of the lid.

2. In a means for molding a concrete vault lid, the combination with a "set" concrete vault body having upstanding walls, and said walls having top edges having a configuration to be complementally formed on

the coacting engaging face of the lid, a lid supporting form spanning said walls and having a forming flange engaging inner portions of said top edges and said supporting form being adapted to receive the concrete to form the lid, said flange being adapted to form an inner sealing space between said top edge and said lid corresponding to the thickness of said flange, means for forming an outer sealing space between said top edge and said lid, and a non-juncture strip disposed between said flange and means to prevent "setting" of the lid to said top edge.

3. In a means for molding a concrete vault lid, the combination with a finished concrete vault body for which a lid is to be molded, said body having upstanding walls having upper edges provided with a configuration to be complementally formed on the coacting engaging face of the lid, a lid supporting arched form spanning said walls and having an outwardly extending sealing

space forming and supporting flange engaging portions of the upper edges to support said form.

4. In a means for molding a concrete vault lid, the combination with a finished concrete vault body for which the lid is to be formed, said body having upper edge portions adapted to form a mold for forming coacting portions of the lid, and mold mechanism coacting with said body for molding the remaining portions of the lid.

5. The herein-described method of molding a concrete lid on a vault, which consists, in supporting and confining the concrete of which the lid is to be molded on and about the vault with the latter in part forming a mold and permitting the lid material to "set" thereon, and in interposing material to prevent the lid to "bond" with the vault.

In witness whereof I have hereunto set my hand.

HENRY S. SCHOPP.
